UNITED STATES PATENT OFFICE.

WILLIAM B. LA POINTE, OF COLUMBUS, OHIO.

SWITCH AND FUSE BOX.

Application filed January 28, 1920. Serial No. 354,703.

To all whom it may concern:

Be it known that I, WILLIAM B. LAPOINTE, a citizen of the United States, residing at Columbus, in the county of Franklin and State of Ohio, have invented a certain new and useful Improvement in Switch and Fuse Boxes, of which the following is a specification.

One object of the invention is to provide an improved and simplified electric switch and fuse box especially for high tension circuits that may be used with safety. Another object is to lock such a box from being tampered with without authority.

15 The invention is characterized principally and generally by the features that in ordinary practice its door or cover may not be opened prior to the opening of the circuit and the circuit may not be closed prior to the closing of the door. Such a box conforms, I believe, to the fire insurance underwriters' requirements that the box shall be kept closed when the switches and fuses are in service. Such a construction also relieves 20 the operator of the dangers and discomforts due to "flashing." Further such a construction prevents attempts to replace a burnt fuse when the circuit is closed.

The invention is embodied in the example 30 herein shown and described, the features of novelty being finally claimed.

In the accompanying drawing—

Figure 1 is a view of the box in side elevation with the switch and door locked, the 35 switch in open position.

Fig. 2 is a vertical section on the line II—II Fig. 4 showing the door closed and locked with the switch closed.

Fig. 3 is a section like Fig. 2 with the door 40 opened.

Fig. 4 is a front elevation looking at the interior of the box.

Fig. 5 is a view like Fig. 1 with the door closed and locked with the switch open.

45 Fig. 6 is a front elevation with the door closed and locked.

In the views 5 designates the box which has a cover 6 hinged to the top of the front.

7, 7 designates the fuses which are removably held in suitable clips 8. The characters

9, 9, designate a knife switch hinged at 10.

10 joined by an insulating bar 11, so as to move in unison on the hinges 10, 10. The

knife switch enters spring clips 10^a, 10^a

55 to close the circuit. The bar 11 is provided with a loop 12. The character 13 designates

a lever of irregular U-form hinged at 14 in the lower end of the box, said lever including the bent operating handle 14^a at the exterior of the box. The upper end of the lever 13 extends through the loop 12 thereby forming a loose link connection between the lever and the knife switch so that by swinging the lever the switch may be opened and closed. A spring 15 (see Fig. 3) connecting the switch with the lever causes a quick throwing of the switch to open position. As regarding the action of this: When the lever is swung outward or toward the door the spring is placed under tension and that causes a quick withdrawal of the switch. In closing the switch the lever compresses the spring thereby permitting pressure exerted with the hand on the lever to close the switch.

75 At the inner side of its upper end the door is provided with lug 16 against which the upper end of the lever abuts when the door is opened so as to preclude the closing of the switch when the door is in that position. At the lower end of its inner side the door is provided with a loop 17 that is engaged by a hook 18 on the lever when the door is closed, said hook preventing the opening of the door prior to movement of the lever to open the switch. The relative location of the parts is such that the hook 18 is completely removed only when the upper end of the lever is in position to be engaged by the lug 16 if the door be opened, said position 80 being that when the switch is opened.

85 To lock the switch when in either open or closed position and prevent unauthorized operation thereof and also the opening of the door I provide a latch 19 pivoted to the handle portion of the lever 13 to engage the switch operating lever in forward position, said latch having at its rear end a hook or head 19^a adapted when the lever is in circuit closing position to engage the rear side of a 90 lug 20 on the side of the box, as shown in Fig. 1, and when the lever is in the open circuit position to engage the forward side of said lug.

95 The door at its front side has pivoted to it a latching lever 21 adapted to be swung to engage lugs 22 on the opposite sides of the box. This latch when locked in engaged position prevents the opening of the door whether the switch is open or closed.

105 To lock or seal the latching lever 19 in either of its two positions and the lever 21

in engaged position I provide a bar 23 sliding in a bracket 24, said bar and bracket being perforated at the proper points to receive the hasp of a padlock 25 to hold 5 said bar 23 in position to sustain the lever 19 against an end of the latched lever 21 and with its headed end 19^a opposed at one side or the other to the lug 20.

The line connections are made at 26 10 and 27.

Normally the slide 23 will not be left in locked or sealed position.

A solenoid 28 actuating an armature 29 can be installed on the side of the box for 15 releasing the latching lever 19 from a distant point. The position of the armature can serve to indicate that the switch is to be opened or is not to be closed until the armature is raised.

20 The forms of the parts can be changed without departing from the gist of the invention as claimed.

What I claim is:

1. A closure for an electric switch including, in combination, a box, a cover therefor hinged thereto at its upper end, a switch operating means consisting of a U-shaped frame pivoted in the lower portion of the box and having one arm operable externally 30 of the box, means on said switch operating means, on the box and on the cover to lock the cover in closed position when the switch is either opened or closed, and means on the cover engaging said U-shaped frame to prevent 35 the operation of the switch operating means when the cover is opened.

2. A closure for an electric switch including, in combination, a box, a cover for the box, a switch operating means operable externally 40 of the box, means on said switch operating means to lock the cover in closed position when the switch is closed, means on the cover to prevent the operation of the switch operating means when the cover is 45 opened, and means common to the switch operating means, and the cover whereby the switch operating means may be latched, in either the open or closed position of the switch and means on the door engaged by 50 said common means to lock the cover in its closed position.

3. A closure for an electric switch including, in combination, a box, a cover for the box, a switch operating device for opening and closing the switch, said switch operating device having means for latching the cover in its closed position, a latching lever carried by said operating device, a lug on the box adapted to be latchingly engaged by said lever in either the opened or closed position 60 of the switch, and means on the box for locking the latching lever in either of its said two positions.

4. A closure for an electric switch including, in combination, a box, a cover for the box, latching lever 21 for the cover and catch therefor on the box, a switch operating device for opening and closing the switch, means on said switch operating device and cover for latching the cover when the switch 70 and cover are in their closed positions, a latching lever 19 carried by said switch operating device, a lug 20 on the box adapted to be latchingly engaged by said lever 19 in either the opened or closed position of the 75 switch, and means 23 on the box for locking the same in either of its said two positions and at the same time locking the cover latch 21, substantially as described.

5. A closure for an electric switch including, in combination, a box, a hinged cover for the box, means for latching the cover upon the box, a switch operating device, means for locking the switch operating device in the closed as well as the open position 85 of the switch, said means also adapted to lock the cover latching device.

6. A closure for an electric switch including, in combination, a box, a hinged cover for the box, means for latching the cover 90 upon the box, a switch operating device, means for locking the switch operating device in the open position of the switch, said means also adapted to lock the cover latching device.

7. A closure for an electric switch including, in combination, a box, a hinged cover for the box, a switch, a switch operating device, a lock for the switch operating device and solenoid having an armature to hold 100 said lock disengaged.

WILLIAM B. LA POINTE.
